UNITED STATES PATENT OFFICE

VINCENT V. VEENSCHOTEN, OF ERIE, PENNSYLVANIA, ASSIGNOR TO NORTHERN EQUIPMENT COMPANY, OF ERIE, PENNSYLVANIA, A CORPORATION OF PENNSYLVANIA

FEED WATER REGULATOR

Application filed November 24, 1926. Serial No. 150,398.

This invention relates to feed-water regulators for boilers and particularly for boilers of special designs which are worked ordinarily at a very high rating. The invention is particularly applicable to boilers consisting of a water drum and a steam drum mounted over the water drum and connected therewith with suitable pipes. One purpose of this arrangement of the drums is to provide steam as free as possible from moisture. One object of my invention is to feed water to the boiler so as to control suitably the water level elevation in the water drum, and a feature of the control is that the amount of steam that is being drawn from the steam drum, that is the load on the boiler, as well as the water level in the lower drum, affect the rate of speed of water to the boiler.

Of the accompanying drawings Fig. 1 is a side elevation of a boiler and a feed-water system which embodies the feature of my invention; Fig. 2 is an end elevation of the same; Fig. 3 is an enlarged detail view of certain portions of the feed-water regulators of the system; Fig. 4 is an elevation of the regulator system applied to a somewhat modified boiler system; and Fig. 5 shows another modification in the boiler system.

Although material modifications might be made in the boiler systems to which my feed-water regulator system is applicable, yet, for the purposes of illustration, I show the system applied to a boiler comprising a main drum 5, a steam drum 6, and a system of water pipes 7. The main drum is mounted over and connected to the pipe system in the ordinary manner so that water or steam is free to flow from the pipes to the main drum, and the steam drum is connected with the main drum by a series of pipes 8. The normal or average water level is maintained in the main drum 5. When in operation, the steam passes from this drum through the pipes 8 to the steam drum 6. But, it will be understood that, when steam is being drawn from the steam drum 6 through the steam main 9 the pressure in the steam drum will fall somewhat below the pressure in the main drum 5 and this fall in pressure is

made use of in the application of the feed-water system.

The feed-water system comprises a feed-water thermostat controller 10 which, as is usual, is connected to the steam space of the drum 5 by means of a pipe 11 and to the water space of the drum 5 by means of pipes 12 and 13. Because of this arrangement the water in the pipe 10 stands substantially at the same general level as the water in the drum 5. The thermostat 10 is mounted on a frame 15 which is fixed in position, and the upper end of the thermostat is fixed to the frame, as is indicated by Fig. 3. The lower end of the thermostat communicates with the head 18, by means of which the tube is pivotally connected to a bell crank lever 19, the lever being pivoted by the fulcrum 20 to the frame 15. The arm 21 of the lever is pivoted to a second lever 22 which, in turn, is connected, by means of a link 23, to the arm 24 of the feed-water valve 25.

In operation, as the water in the drum 5 lowers, some of the water will pass out of the thermostat 10 and will be replaced by steam. As a consequence the tube will expand and, assuming the fulcrum 27 to be fixed, the outer end of the lever 22 will be raised, raising the arm 24 and opening more the feed-water valve 25. Aside from the lever arrangement this is substantially the same as the operation of the well known "Copes" feed-water regulators.

However, I provide in the system a second thermostat tube 30 which is inclined or, preferably, is vertically mounted on a vertical frame 31. The upper end of the tube 30 is adjustably fixed by means of the nuts 32. Also, the upper end of the tube 30 is connected, by means of a pipe 33, with the steam drum 6, and the lower end is connected, by means of a pipe 34 and the pipe 13, with the water space of the drum 5. The lower end of the thermostat 30 is pivotally connected to the lever 22 by means of the fulcrum 27. It will thus be seen that, if there is no change in the tube 30, the operation of the feed-water valve will be as hereinabove set forth by means of the tube 10. But, if, for any reason, the tube 30 should expand

or contract this also will affect the movement of the lever 22 and the amount of opening of the feed-water valve.

When in operation, as steam is drawn from the steam drum 6 there will be a drop in pressure in this drum owing to the somewhat restricted connection between the two drums by means of the pipes 8. As a consequence of the pressure in the drum 5 being greater than in the drum 6, the water in the pipe 13 will be forced upwardly into the tube 30, and, hence, in normal operation, the water will stand at a certain level in the tube 30. It is to be understood that the length of this tube may be sufficiently great to meet any of the requirements of the boiler system, and the water level in this tube will depend somewhat on the water level in the drum 5, but largely, on the difference in pressure between the two drums. When the load on the boiler is increased so as to draw from the drum 6 a greater amount of steam the pressure therein will drop somewhat and the water will rise in the tube 30, thus cooling somewhat the tube and causing it to contract. As a consequence the fulcrum 27 will be elevated, the link 23 will be raised, and the opening of the valve 25 will be increased so as to pass into the system more water to take care of the increase of the load on the boiler. Conversely, if less steam is drawn from the drum 6 the pressure therein will increase, the water in the tube 30 will sink, and the tube will expand, allowing the feed-water valve to close somewhat more and thus reduce the flow of water to the boiler.

In this way the vertical thermostat in general controls the change of feed desirable to take care of changes in load, and the inclined thermostat compensates for any over or under feeding which would tend to change the water level in the main drum too much. The inclined thermostat is also a safety factor, as, being inclined, variations in water level which exceed the desired limit will affect the temperature sufficiently to either open wide or entirely close the feed-water valve, as the case may be.

But the inclined tube has an additional secondary purpose and that is to retard the change in water inflow so as to lessen the burden on the fire when the change occurs. When the heavy load comes on, the steam flow effect will take care of the increased water flow needed. This effect, however, will lag in its action and the water will sink temporarily materially because of the increased flow of steam. The inclined tube will open wider the water valve to compensate for this lag, allowing more water to flow than is required until the normal level is again reached. When this level is reached, the inclined tube will provide exactly the same amount of water as before, as its effect

on the valve for a given water level elevation will always be the same. But the steam flow effect will supply the needed increase in water so that the level will again remain constant. In the meantime, however, when the fire is struggling to meet the increased needs, the water level effect on the vertical tube will cause it to buck against the inclined tube and retard the increased opening of the water valve by the inclined tube and, hence, to reduce the increased flow of water until the fire has a chance to catch up.

It is true that these two regulators at times buck against each other, but the effect of the water changes on the inclined tube is far greater than on the vertical tube. Hence, no particular disadvantage can result and the main function of the inclined tube is in no way affected.

Also, by connecting the vertical tube beneath the water level, maintenance of water at all times in the vertical tube is provided for. If not so connected, a tank would have to be connected in the pipe 34 to supply water to the vertical tube as the water therein rose. By connecting the lower end of the vertical tube to the water pipe of the inclined tube, the installation is much simplified and the water cannot be inadvertently forced out of the vertical tube.

It will be seen that my invention is based upon the difference in pressure between the steam in the two drums. But the invention applies equally as well to any boiler system having a difference in the steam pressure at two points. To illustrate this, Fig. 4 indicates a boiler feed-water regulator system in which the boiler 35 has a super-heater 36 connected therewith in an ordinary manner, shown diagrammatically in the figure. The steam flows from the boiler through the super-heater and finally through the steam main 37. In this instance the regulator 30 has its lower end connected to the boiler 35, as in the former case, but has its upper end connected to the super-heater pipe 39 by means of a pipe 38. As is well understood the steam pressure at the point of connection of the pipe 38 to the pipe 39 would be, in normal operation, lower than the steam pressure in the boiler 35. As a consequence the operation of the regulator 30 in this instance would be substantially the same as the operation in case of Figs. 1 and 2.

Various other methods of connecting up the system would produce substantially the same results. In Fig. 5 I have illustrated a system in which the regulator 30 is connected between the main drum of the boiler 40 and the steam main 41 and in parallel with a valve 42 in the pipe 43 connecting the steam main to the boiler. By this arrangement, there will be more or less of a drop of pressure through the valve, and, hence, more or less operation of the regu-

lator 30, as variations in the demand for steam occur. The effect of the regulator 30 can be varied by varying the size of the orifice of the valve 42.

I claim as my invention:—

1. The combination of a boiler and a feed-water regulator system therefor, said boiler comprising a feed-water valve, a water space, an adjacent steam space, and a more remote steam space, said regulator system operatively communicating with the said water space, with the said adjacent steam space, and with the said remote steam space, and means operatively connecting said regulator system with said valve, said regulator system comprising two feed-water regulators, each of said regulators communicating with said water space, one communicating with said adjacent steam space materially above the normal water level elevation therein and the other with said remote steam space, each of said regulators being independently operatively connected to said water space. 70
2. The combination of a boiler and two thermostat tubes, said boiler having a feed-water valve and a steam and a water space and a steam main communicating with said steam space, one end of each of said tubes communicating with said water space, the other end of one tube communicating with said steam space adjacent the point of communication therewith of said main the other end of the other tube communicating with said steam main at a point remote from the point of communication of said main with said steam space, each of said tubes being operatively connected with said valve. 75
3. The combination of a boiler and two thermostat tubes, said boiler having a feed-water valve and a steam and a water space, and a steam main communicating with said steam space, one end of each of said tubes communicating with said water space, the other end of one tube communicating with said steam space adjacent the point of communication therewith of said main, the other end of the other tube communicating with said steam main at a point remote from the point of communication of said main with said steam space, each of said tubes being operatively connected with said valve, one of said tubes being inclined more and the other less than 45° to the horizontal. 80
4. A combination of a boiler and a feed-water regulator system therefor, said boiler comprising a steam and a water space and a feed-water valve, and a steam main connected with said steam space, said regulator system comprising two thermostats, the respective ends of one thermostat being connected to the steam space and the water space of the boiler, the other thermostat being connected to the water space of said boiler and to said steam main, the remote ends of said thermostats being fixed, and levers operatively connecting together the adjacent ends of said thermostats and operatively connecting them to said feed-water valve. 85
5. The combination of a boiler and a feed-water regulator system therefor, said system comprising a thermostatic tube operatively connected at one end to the boiler below the water line, means depending on the operation of the boiler for maintaining a water column in said tube and for varying the length of said column directly with the variations in load on the boiler, a feed-water valve for passing water into the boiler of the system, and means operatively connecting said tube and valve and arranged to open said valve as the tube contracts in length. 90
6. The combination of a boiler and two feed-water regulating thermostats, said boiler having a feed-water valve, a water space, a steam space adjacent said water space and a steam space more remote from said water space, each thermostat communicating at all times with said water space, one communicating at all times with said adjacent steam space and the other with said remote steam space, the adjacent ends of said thermostats being operatively connected with each other and with said valve, the remote ends of said thermostats being fixed. 95
7. In a steam boiler system having a steam main and a feed-water valve for passing water to said boiler, in combination with means for increasing the magnitude of the opening of said valve directly with the increases in differences in static pressures of the steam in said boiler and in said steam main, said means comprising a feed water regulator operatively connected with said valve and with said main and also with said boiler. 100
8. The combination of a boiler and two thermostat tubes, a steam drum operatively connected to said boiler, said boiler having a feed-water valve and a steam and a water space and a steam main communicating with said steam space, one end of each of said tubes communicating with said water space, the other end of one tube communicating with said steam space, and the other end of the other tube communicating with said steam drum, each of said tubes being operatively connected with said valve. 110
9. A combination of a boiler and a feed-water regulator system therefor, said boiler comprising a steam and water drum, a steam drum, and a feed-water valve, and a steam main connected with said steam drum, said regulator system comprising two thermostats, the respective ends of one thermostat being connected to the steam space and the water space of the steam and water drum, the respective ends of the other thermostat 115
10. The combination of a boiler and a feed-water regulator system therefor, said boiler comprising a steam and water drum, a steam drum, and a feed-water valve, and a steam main connected with said steam drum, said regulator system comprising two thermostats, the respective ends of one thermostat being connected to the steam space and the water space of the steam and water drum, the respective ends of the other thermostat 120
11. The combination of a boiler and a feed-water regulator system therefor, said boiler comprising a steam and water drum, a steam drum, and a feed-water valve, and a steam main connected with said steam drum, said regulator system comprising two thermostats, the respective ends of one thermostat being connected to the steam space and the water space of the steam and water drum, the respective ends of the other thermostat 125
12. The combination of a boiler and a feed-water regulator system therefor, said boiler comprising a steam and water drum, a steam drum, and a feed-water valve, and a steam main connected with said steam drum, said regulator system comprising two thermostats, the respective ends of one thermostat being connected to the steam space and the water space of the steam and water drum, the respective ends of the other thermostat 130

being connected to the water space of said steam and water drum and to said steam drum, the remote ends of said thermostats being fixed, and levers operatively connecting together the adjacent ends of said thermostats and operatively connecting them to said feed-water valve.

In testimony whereof, I hereunto set my hand.

16 VINCENT V. VEENSCHOTEN.
